CRACKING HEAVY OILS IN PRESENCE OF OXYGEN

Richard M. Deanesly, Hinsdale, Ill., assignor to
 Universal Oil Products Company, Chicago, Ill.,
 a corporation of Delaware

Application February 18, 1948, Serial No. 9,252

2 Claims. (Cl. 196—65)

1

This invention relates to an improved method and means for effecting the autothermic cracking of relatively heavy oils, gas oils or heavier, in order to produce lower molecular weight hydrocarbons such as olefins, diolefins, aromatics and the like.

The high temperature vapor phase cracking of heavy hydrocarbon oils has been a rather difficult procedure because of the fact that a tar fog is formed which contains more or less solid particles of carbon. Thus, when the fog settles and adheres to equipment beyond the zone of formation, that portion of the cracking apparatus and the separating equipment generally becomes plugged with a coke formation. When the cracking is effected by mixing air or oxygen with the preheated oil stream to obtain the desired cracking temperatures by internal oxidation, the process has been given the general name of autothermic cracking.

It is the principal object of the present invention to provide an operation which effects an efficient conversion of heavy oils to desirable lower boiling and lower molecular weight products comprising particularly olefins, dienes and aromatics, while simultaneously trapping and eliminating the tar fog from the product stream.

It is also an object of the invention to provide an improved apparatus arrangement for carrying out the autothermic cracking of heavy oils, the unit being one which permits improved quenching, and one which may be operated continuously with little or no trouble from coking and plugging.

A desirable feature of the present invention resides in passing the autothermically cracked products through a fluidized bed of coke-like particle being maintained in a confined zone adjacent to and in communication with the cracking zone. The particle bed provides a zone for completing the autothermic reaction, while the tar fog, resulting from the cracking operation, is trapped on the particles and is cracked progressively to increase the volume of coke present, the surplus of which may be drawn off from the fluidized bed. Thus, the resulting vaporous product stream may be discharged from the upper portion of the fluidized particle zone in a substantially clear form and pass to conventional fractionation and recovery apparatus, with little or no trouble arising from coking in the recovery equipment.

Broadly, the improved method of autothermic conversion of a heavy oil stream as provided by this invention, comprises, preheating the heavy

2

oil stream and dispersing it in admixture with air, or a stream containing free oxygen, into a relatively small confined reaction zone, effecting the autothermic cracking of the oil stream under substantially adiabatic and short residence time conditions, passing the resulting products of lower molecular weight hydrocarbon gases and vapors, coke, and tar fog from the reaction zone to the lower portion of a fluidized bed of coke-like particles maintained in direct and open communication with the outlet of the reaction zone, passing the product stream upwardly through the fluidized bed of particles and effecting simultaneously the completion of the thermal conversion and the trapping of the tar fog, continuously discharging a substantially clear product stream from the upper portion of the particle bed and continuously withdrawing excess coke-like particles from the fluidized bed, the excess being provided by the progressive cracking of the tar fog produced in the cracking operation.

In a more specific embodiment of the operation, the operating pressure within the reaction zone is maintained relatively low, preferably below 3 atmospheres, while the cracking temperature may vary from 1200 to 1700° F. depending upon the principal products sought and/or economically favorable from the standpoint of the charging stock employed. Preferably, the air stream as well as the oil stream, is preheated and mixed therewith in controlled proportions to effect the oxidation of a part of the hydrocarbon stream in an exothermic reaction and to provide the desired temperature necessary to effect an efficient endothermic cracking reaction of the remainder of the hydrocarbon stream that accompanies, in the conversion zone, the hot oxidation products of the exothermic reaction. As may be deemed desirable, steam or other diluent gas may be mixed with the reactant streams to minimize the carbon formation within the conversion zone.

In an alternate, and very desirable specific operation, the fluidized particle bed may be employed as a quenching zone to effect a rapid cooling of the cracked product stream and thus prevent polymerization and side reactions from taking place while simultaneously trapping the tar fog which is produced. In this embodiment the fluidized particles are circulated through a cooling zone which may be built integral with or separate from the main vessel as convenient.

The fluidized particle bed may comprise coke-like particles built up from the coke and tar fog, as noted hereinabove, however, a finely divided refractory type of particle may be used to collect

the tar fog and continuously or intermittently withdrawn for burning and removing the carbonaceous deposit in a separate regenerator. In still another embodiment of this improved high temperature conversion and tar fog removing process, a finely divided material which has catalytic properties, suitable for the particular conversion, may be employed within the adjacent fluidized bed, to aid in the production of the lower molecular weight products and serve as a material to absorb and collect the carbonaceous material.

The high temperature cracking in the reaction zone is carried out in a manner to have only a short residence time under substantially adiabatic conditions, thus, a small, elongated, and refractory lined temperature resistant reaction chamber is preferably provided for the cracking portion of the unit. Suitable external insulation around the reaction chamber is provided to prevent loss of heat therefrom and to insure an operation which is as closely adiabatic as possible. It is a particular feature of the improved design of the apparatus of this invention to have the particle bed chamber or quenching chamber connect directly with the outlet end of the reaction chamber so that the reaction products may be discharged rapidly into the fluidized bed.

The accompanying drawing serves to illustrate varying forms of the improved conversion apparatus for the autothermic cracking of heavy oils, and the following description thereof will serve also to explain more fully the conversion and contacting operation of this invention.

Figure 1 of the drawing is an elevational view, shown diagrammatically, of one form of apparatus for carrying out the improved autothermic cracking operation of heavy oils.

Figure 2 of the drawing, shows an alternate construction of the lower end of the conversion apparatus, at the zone where the reaction chamber connects with the fluidized bed chamber.

Referring now to Figure 1 of the drawing, there is shown a small vertically positioned reaction chamber 1 which is below and connects with a larger vertically positioned fluidized particle chamber 2. The interior of the chamber 1 is provided with a heat resistant refractory 3, comprising an insulating cement, or a ceramic type of material, suitable for withstanding temperatures of the order of 2000° F., or higher, depending upon the particular cracking range which may be desired. The lower end of the chamber 1 has an inlet nozzle 4, adapted to receive a mixed reactant stream passing by way of line 5 to the dispersion or atomizing nozzle 6. In this embodiment, the nozzle is placed in the end of the cracking zone just inside of the inlet opening 4.

The heavy oil feed stream to the unit is charged through line 7 to a heat exchanger 8, and from the latter it is passed through line 9 and control valve 10, to the line 5. The charge stream is thus preheated, and preferably vaporized, by heat exchange with the product stream which is discharged from the upper end of the unit through line 11 to the heat exchanger 8. Air, or oxygen, preheated or not as may be desired, is charged through line 12 and control valve 13 to line 5 and is mixed with the preheated oil stream, in a controlled proper proportion with the latter, to provide a mixed reactant stream which may be discharged through the nozzle 6 into the reaction chamber 1 to effect the autothermic cracking of the heavy oil to produce the desired lower boiling hydrocarbon products.

Provision is also made at the lower end of the apparatus for admitting steam through line 14, having valve 15, so that when desired, a small quantity of steam may be mixed with the reactant stream to provide a diluent and to provide further control over the primary conversion. Still another line 16, having valve 17 is provided to connect with line 5, and as indicated may be used to charge a fuel gas to the unit, to provide heat for starting up the unit, or alternatively, to provide additional heating fuel for oxidation within the conversion zone where alternative reaction conditions are deemed desirable.

In a preferred operation of the unit, the reactant stream is charged continuously to the lower end of the chamber 1 and reaction products are continuously discharged after relatively short periods of contact and reaction time within the chamber, to the lower end of the upper chamber 2 which maintains therein a fluidized bed of coke-like particles 18 as a contacting and tar fog collecting medium for the reaction chamber products. A relatively low superatmospheric pressure is preferably maintained in the reaction zone, however, sufficient pressure is utilized to insure the passage of the reaction products upwardly through the bed 18 and to adequately fluidize it as the stream flows upwardly therethrough.

The reaction products comprising lower boiling hydrocarbon gases and vapors, coke and tar fog, pass continuously from the chamber 1 to the lower end of chamber 2; thus, in this improved operation, the coke and tar fog will be trapped and absorbed within the fluidized bed 18, while the gaseous products are permitted to undergo further adiabatic conversion to substantial completion, or alternately, may be quenched progressively as they pass upwardly through the bed to be discharged in a substantially clear and stable form at the top of chamber 2, and at a reduced temperature of the order of 600° to 800° F., so that further cracking and polymerization reactions are stopped. The tar fog which is produced and passed from the reaction chamber 1 is cracked progressively to provide additional coke in the fluidized bed 18 so that a surplus may be continuously withdrawn from the unit and discarded. In this drawing, the upper extremity of the fluidized coke bed is indicated by the broken line 19, and an outlet line 20, having a control valve 21, provides means for withdrawing the excess coke from an intermediate point in the wall of the quenching chamber 2.

Figure 2 of the drawing, shows an alternate arrangement and method for connecting the reaction chamber with the quenching chamber. The reaction chamber 23 is placed angularly with respect to a vertically positioned quenching chamber 24, which in turn has a long tapering cone-like lower head 25. The lower portion of chamber 23 connects with the lower head 25, so that the reaction products from the chamber 23 thus flow downwardly into the head 25 and turn upwardly into the fluidized quenching bed 26. The latter may comprise a fluidized bed of coke-like particles, such as described in connection with Figure 1 of the drawing, or a bed of finely divided particles, either inert or of a catalytic nature, suitable to remove the tar fog upon contact with the reaction product stream. In this embodiment of the unit, the chamber 23 and the lower tapering head 25 are each provided with a refractory heat resistant type of liner 27 suitable for withstanding high temperature cracking conditions.

At the upper and inlet end of the reaction chamber 23, the mixed reactant stream is charged through line 28 and dispersion nozzle 29, with the proper proportion of pre-heated oil to oxygen being controlled to effect the desired conversion reaction. Oil is charged to the line 28, through line 30, having control valve 31, while the pre-heated air, or other oxygen containing stream, is charged through line 32 and control valve 33. The third line 34, having control valve 35, provides means for charging steam or other hot diluent gas to the unit in admixture with the air and oil stream, when such may be desired in carrying out the autothermic reaction.

A heating coil 42, placed within the chamber 24 and connecting with line 32 provides means for transmitting heat from the bed 26 to the air stream, while another coil 43, connecting with line 34, similarly transmits superheat to the steam stream which may be charged to the reactor 23.

An inlet 36, at the lower end of the tapering head 25, provides means for charging a fuel gas and air to the unit to minimize combustion of the reactant stream, or alternately, to provide means for warming up and starting the unit. Fuel gas is conducted to the inlet 36 through line 37, valve 38 and line 39, while the additional air stream may be conducted through line 40 and valve 41 to the line 39 and inlet 36.

The autothermic cracking of heavy oils to provide lower mol weight olefins and aromatics may be carried out in the apparatus embodiment of Figure 2 in substantially the same manner as that described in connection with Figure 1, the reaction products of the lighter hydrocarbon vapors and gases, coke and tar fog are passed to the lower portion of the fluidized bed chamber to fluidize the coke-like particles 26 maintained in the chamber, whereby the bed serves simultaneously to quench the product stream and substantially eliminate the tar fog therefrom.

This latter embodiment provides, however, for a slightly different and optional operating procedure, in that fuel gas and air may be charged independently to the lower end of the unit and provide combustion products into which the oil stream may be atomized. Thus, a lesser amount of the charge may be used for autothermic cracking within the reaction chamber 23, the necessary endothermic heat required being supplied from the extraneous fuel charged via line 37.

It is not intended to limit the process and apparatus of this invention to the exact construction and arrangements which have been shown in the drawing, for obviously, variations may be made in the positioning and arrangement of the different sections of the unit, and fall within the scope of this improved means for carrying out autothermic cracking of heavy oils. Particles separating means, such as the usual, well-known, centrifugal or electrical precipitator types of apparatus, may be used if desired in the upper part of the quenching chamber to effect the removal of solid particles from the gaseous product stream, prior to discharging it through line 11.

Also, it is not intended to limit the pre-heating of the air and the heavy oil charge streams to that which may be obtained in heat exchangers such as shown, for additional heaters or heat exchange means may be employed to bring the streams to a desirable charging temperature.

I claim as my invention:

1. In a process for the autothermic cracking of a relatively heavy hydrocarbon oil stream to

produce lower boiling and lower molecular weight hydrocarbons, the improved method of operation which comprises, pre-heating said heavy oil stream and dispersing it continuously in admixture with a free-oxygen containing stream into a relatively small confined reaction zone, controlling the proportions of oil and oxygen-containing streams in the mixture and effecting a substantially adiabatic autothermic cracking of said oil within said reaction zone at a temperature of from 1200 to 1700° F. while maintaining a relatively low superatmospheric pressure therein of less than 3 atmospheres, said adiabatic autothermic cracking being of a sufficient magnitude to form a product stream containing a substantial amount of tar fog and lower molecular weight hydrocarbon vapors, passing the products of oxidation and cracking in a continuous stream to a fluidized bed composed predominantly of coke-like particles being maintained contiguous with the outlet of said reaction zone, passing the product stream upwardly through said bed and therein trapping tar fog resulting from said cracking, while controlling the flow of the vaporous products to provide fluidization of said coke-like particles within said bed, continuously discharging a substantially clear stream of lower molecular weight hydrocarbon products from said fluidized bed, effecting the continuous addition of coke-like particles to said bed by the continuous heating and progressive cracking of said tar fog trapped therein, and withdrawing a continuous stream of surplus particles whereby to maintain a substantially constant depth fluidized bed of particles.

2. In a process for the autothermic cracking of a relatively heavy hydrocarbon oil stream to produce lower boiling and lower molecular weight hydrocarbons, the improved method of operation which comprises, pre-heating said heavy oil stream and dispersing it continuously in admixture with a free-oxygen containing stream into a relatively small confined reaction zone, controlling the proportions of oil and oxygen-containing streams in the mixture and effecting a short contact time and substantially adiabatic autothermic cracking of said oil within said reaction zone at a temperature of from 1200 to 1700° F. while maintaining a relatively low superatmospheric pressure therein of less than 3 atmospheres, said adiabatic autothermic cracking being of a sufficient magnitude to form a product stream containing a substantial amount of tar fog and lower molecular weight hydrocarbon vapors, passing the products of oxidation and cracking in a continuous stream to a quenching zone, said quenching zone being maintained contiguous with the outlet of said reaction zone and having therein a fluidized bed composed predominantly of coke-like particles, passing the product stream upwardly through said bed and simultaneously quenching the vaporous products and trapping tar fog resulting from said cracking, while controlling the flow of said vaporous products to provide fluidization of said coke-like particles within said quenching zone, continuously discharging a substantially clear stream of lower molecular weight hydrocarbon products from said quenching zone from above said fluidized bed at a temperature precluding further cracking, effecting the continuous addition of coke-like particles to said bed by the continuous heating and progressive cracking of said tar fog trapped therein, and withdrawing a continuous stream of surplus particles whereby to maintain

a substantially constant depth fluidized bed of particles within said quenching zone.
